[57] **CLAIM**

The ornamental design for a combined bottle storage and dispensing rack, as shown and described.

DESCRIPTION

FIG. 1 is a diagrammatic perspective view of the combined bottle storage and dispensing rack in full lines with bottles shown in broken lines representing environmental association matter being for illustrative purposes only and forming no part of the claimed invention.

FIG. 2 is a right side elevational view of the combined bottle storage and dispensing rack, the left side view, as well as the front and rear elevational views, being mirror images of the right side elevational view.

FIG. 3 is a bottom plan view thereof; and,

FIG. 4 is a top plan view thereof.
